United States Patent Office

Des. 174,003
Patented Feb. 8, 1955

174,003

MICROPHONE

Burt E. Schell, Jr., Mundelein, Ill., assignor to Shure Brothers, Incorporated, Chicago, Ill., a corporation of Illinois

Application February 17, 1954, Serial No. 29,087

Term of patent 14 years

(Cl. D26—14)

Fig. 1

To all whom it may concern:

Be it known that I, Burt E. Schell, Jr., a citizen of the United States, residing at Mundelein, in the county of Lake and State of Illinois, have invented a new, original, and ornamental Design for Microphone, of which the following is a specification, reference being had to the accompanying drawings forming a part thereof, in which:

Fig. 2 is a front elevational view thereof, and

Fig. 3 is a side elevational view taken from the right of Fig. 2.

I claim:

The ornamental design for a microphone, substantially as shown.
